DESIGN FOR A FLOODLIGHT

Carl F. Haas, Lakewood, Ohio, assignor to
Westinghouse Electric & Manufacturing Com-
pany, a corporation of Pennsylvania

Application October 9, 1934, Serial No. 53,528

Term of patent 7 years

To all whom it may concern:

Be it known that I, Carl F. Haas, a citizen
of the United States, residing at Lakewood, in
the county of Cuyahoga and State of Ohio, have
invented a new, original, and ornamental Design
for a Floodlight, of which the following is a
specification, reference being had to the accom-
panying drawing, constituting a part hereof.

Figure 1 is a plan view of a floodlight showing
my new design;

Fig. 2 is a side elevational view of the flood-
light of Fig. 1; and

Fig. 3 is a rear elevational view of the flood-
light of Fig. 1.

I claim:

The ornamental design for a floodlight sub-
stantially as shown.

In testimony whereof, I have hereunto sub-
scribed my name this 28th day of Sept., 1934.

CARL F. HAAS.
